ART OF MANUFACTURING PARAFFIN

Filed Nov. 20, 1925

Inventor
Clarence A. Ward

By his Attorney *John A. Ward*

UNITED STATES PATENT OFFICE

CLARENCE A. WARD, OF LINDEN, NEW JERSEY, ASSIGNOR TO STANDARD OIL DEVELOPMENT COMPANY, A CORPORATION OF DELAWARE

ART OF MANUFACTURING PARAFFIN

Application filed November 20, 1925. Serial No. 70,413.

The present invention is directed to the art of treating hydrocarbon oils. The invention is directed more particularly to an improved process of obtaining paraffin as well as increased yields of other valuable products from hydrocarbons, as will be readily understood from the following description.

The drawing is a semi-diagrammatic view in elevation of an apparatus suitable for carrying out my invention and illustrates the flow of material.

Paraffin of commerce for a long time has been manufactured by the well-known process wherein a paraffin-containing distillate of desirable characteristics is first chilled to a point sufficient to separate out by solidification substantially all of the paraffin contained therein. The chilled distillate is then passed through the paraffin presses whereby a substantial quantity of the paraffin content, admixed with a certain proportion of oil, is separated from the main bulk of oil present. The material so separated, which is termed a "slack wax", is usually treated with acid for the removal of impurities and for improving the color of the product, and is then sweated to remove the liquid oil present, whereby a crude scale wax is obtained as a residuum. The sweating process is usually carried out by placing the solidified material, that is the slack wax, in an enclosed chamber, the temperature of which can be regulated as desired. The temperature of the wax is then raised very slowly, whereby the more liquid portions of the wax sweat out and are withdrawn from the compartment. As the process continues, the wax content of the liquid removed increases until toward the end of the operation it has practically the same composition as the original stock charged to the sweaters. The first runnings, or the more liquid fractions obtained as described and which contain approximately 30% of wax, are termed "foots oil".

A foots oil as ordinarily obtained contains appreciable proportions of paraffin which can be separated therefrom by proper treatment. Normal operating practice as ordinarily carried out has long required that the foots oil be recycled with a certain amount of

fresh paraffin distillate and again put through the process as described above. The foots oil, however, ordinarily contains a much greater proportion of paraffin than does the paraffin distillate, so that the amount of press space required for pressing a given volume of foots oil is very much greater than is required for pressing a corresponding volume of the fresh paraffin distillate. The use of an excessive amount of press capacity for handling a comparatively small volume of foots oil is a serious problem to refiners having a large volume of paraffin distillate to handle, particularly where the available press capacity is at all limited. Although it has heretofore been considered that the recirculation of a foots oil was more or less essential for the satisfactory pressing of a fresh paraffin distillate, I have observed that this is not necessarily the case, as is shown hereinafter, especially when using a paraffin distillate which in the course of its manufacture has been subjected to an efficient rectification step during its separation from lighter and heavier ends.

The various advantages as set forth below can, as I have found, be realized by concentrating the foots oil from the sweating process by removing by distillation means approximately 40% by volume comprising the lighter portions of the oil, whereupon the 60% residuum will not need to be returned to paraffin distillate to be rechilled and repressed as in the ordinary procedure as outlined above, but can be sweated satisfactorily, whereby substantially complete separation of a paraffin of high quality follows. Although the distillation step mentioned may be carried out under a vacuum if desired, I have found that satisfactory results are realized by reducing the foots oil by means of fire and steam, since all that is necessary is to avoid the possibility of substantial cracking of the stock under treatment.

As an example of my invention, a sample of foots oil containing approximately 33.2% of paraffin, as indicated by the Holde method of determining this constituent, was distilled by fire and steam to approximately 60% bottoms while maintaining the temperature of

the oil below 600° F. during the entire period of heat treatment. The overhead distillate collected was found to have a gravity of about 38.1° Bé. and a viscosity at 100° F. of 47 seconds Saybolt. The residuum obtained was found to contain 85.5% of the total quantity of paraffin originally present in the foots oil. It was found that this residuum did not need to be chilled and pressed 10 as in the case of an ordinary paraffin distillate, but due to the greater proportion of paraffin contained therein, could be sweated directly, thereby yielding 34.2% of a crude scale wax having a melting point in this 15 case of 124° F. The crude scale wax so obtained was then treated in the usual manner and a finished paraffin of high quality produced.

As another example, a sample of a foots 20 oil containing 29.6% paraffin, as shown by the Holde method, was distilled approximately to a 60% bottoms by means of fire and steam at temperatures below 600° F. This residuum, as in the example shown 25 above, was sweated directly, and after sweating yielded 27.4% of a crude scale wax having a melting point of 122.7° F. This product also yielded a paraffin of commercial value when finished in the usual manner.

20 The extent to which the foots oil is reduced by distillation in the manner set forth above depends, of course, upon its paraffin content, but I have found if such an oil be reduced to a bottom or residuum possessing 35 an oil content of approximately 50% and which residuum solidifies more or less completely at approximately 100° F., the paraffin can be removed readily therefrom by direct sweating without preliminary chilling 40 and repressing the material. The importance of this method of handling the foots oil may be realized when it is considered that by treating in the manner as set forth, a foots oil having a paraffin content of 30% and 45 thereby eliminating the necessity of repressing this material, there is released sufficient press capacity to accommodate five times its volume of a paraffin distillate containing about 6% of paraffin. In other words, ap- 50 proximately five times the pressing capacity is required for pressing a foots oil as is required for pressing the same volume of a fresh paraffin distillate. This excessive use of press capacity can be avoided by treating 55 a foots oil in the manner as set forth.

Referring to the drawing reference character 1 designates a tank containing paraffin or wax distillate which is kept liquid by steam coil 2. The oil is forced under high pressure 60 by pump 3 through line 4 to a heat exchanger 5 and then to a chiller 6 which is cooled by brine. Brine circulation system is not shown since it is well known in the art. Chilled oil and wax solidified by cooling then pass to 65 wax press 7 and wax is filtered from the bulk

of the oil which then flows through heat exchanger 5 and to storage (not shown).

Wax is taken from the presses and put in a steam jacketed agitator 8 for acid and other treatment as is well known and which forms no part of the present invention. The purified wax now in a molten state is pumped to a heated feed tank 9^a and thence to sweater 9 by a line 10. The sweater is a well known piece of refinery equipment and need not be described.

Wax is solidified in layers in the sweater which is provided with pans 11 below each layer of solid wax which is indicated by 12. The temperature is then slowly raised by steam coils (not shown) and the "foots oil" running down into pans 11 is withdrawn by a pipe 13 and pumped to a still 14. The oil contains wax and the line 13 may be heated to prevent solidification. Still 14 is shown 85 as operating at normal atmospheric pressure with a steam spray 15 but a vacuum still may be used. Distillate is collected and condensed in condenser 16 and pumped to storage (not shown).

The unvaporized portion of residuum is withdrawn from the still and pumped through line 17 to sweater feed tank 9^a and is then recycled through the sweating process.

Operation of the sweater is a batch method and "foots oil" is first collected. After all of the "foots oil" has been removed from the sweater "intermediate wax" is melted and is collected in a tank 18. "Intermediate wax" 100 is customarily resweated. Paraffin wax substantially free of oil now remains in the sweater and is finally melted and collected in tank 19.

Although I have shown the reduced "foots 105 oil" returned to sweater 9 and mixed with fresh slack wax, it may be resweated alone in a separate sweater as is apparent.

Although I have described my process as applicable to the treatment of a foots oil, it 110 is to be understood that any hydrocarbon fraction containing a relatively high proportion of paraffin, for example 20% or higher, may likewise be treated. In the case of fractions containing less than 30% paraffin, the 115 reduction with fire and steam would be carried out in a manner to obtain a larger percentage of overhead distillate than that set forth in the examples given, while in fractions containing substantially more than 30% 120 paraffin the reduction by heat would not be carried so far but a larger proportion of residuum would be left for the sweating treatment.

While in describing my invention I have 125 referred to certain specific details, it will be understood that these are illustrative only and not limitative. Nor is my invention to be understood as depending upon the accuracy of any theory or reason suggested to ex- 130

plain the advantageous result. On the contrary, the invention is to be regarded as limited only as defined in the following claims, in which it is my intention to claim all novelty inherent in my process as broadly as the prior art permits.

5 What I claim is:

1. The process of obtaining paraffin from a petroleum distillate containing more than 10 20% of paraffin comprising redistilling without substantial cracking whereby a residuum is obtained substantially solid at approximately 100° F., cooling the residuum and sweating it to obtain paraffin.
- 15 2. The process of obtaining paraffin from a foots oil, which comprises separating the foots oil by distillation to approximately 600° F. into a volatile portion and a residuum, cooling and then sweating said residuum.
- 20 3. The process of obtaining paraffin from a foots oil, which comprises reducing said foots oil substantially to a 60% bottoms by means of distillation at a temperature below 25 600° F., cooling and then sweating said bottoms.
4. The process of obtaining paraffin from a foots oil, which comprises reducing said foots oil by means of fire and steam substantially 30 to a 60% bottoms, cooling and then sweating said bottoms.
5. The process of obtaining paraffin from a petroleum distillate, which comprises concentrating said distillate at temperatures below 35 the cracking temperature to a residuum, solid at room temperature, which can be sweated directly.
6. The process of obtaining paraffin from a petroleum distillate, which comprises concentrating said distillate at temperatures below 40 the cracking temperature to a residuum containing approximately 50% of a paraffin, cooling and then directly sweating said residuum.
